Attorney

UNITED STATES PATENT OFFICE.

WILLIAM S. FELL, OF NEW ORLEANS, LOUISIANA.

WINDOW-LATCH.

1,261,913.

Specification of Letters Patent.

Patented Apr. 9, 1918.

Application filed December 1, 1917. Serial No. 204,866.

To all whom it may concern:

Be it known that WILLIAM S. FELL, a citizen of the United States, residing at New Orleans, in the parish of Orleans and State 5 of Louisiana, has invented certain new and useful Improvements in Window-Latches, of which the following is a specification, reference being had to the accompanying drawings.

10 This invention relates to window latches, and particularly to latches which fall by gravity to an operative position over the meeting rail of the lower sash when the lower sash is lowered, this latch preventing 15 any opening of the lower sash unless the latch be designedly released.

My invention has for its object the provision of means for positively throwing the locking member of the latch downward over 20 the upper bar of the lower sash when the upper and lower sashes are shifted to a closed position.

25 A further object is the provision of means for preventing a knife blade being inserted between the meeting rails of the sashes so as to raise the latch when the latter is lowered.

A further object is to provide means whereby the tongue of the latch will act as an anti-rattler.

30 Other objects will appear in the course of the following description.

My invention is illustrated in the accompanying drawings, wherein:—

Figure 1 is a front elevation of a pair of 35 window sashes with my latching device applied thereto, the latching device being in its latching position;

Fig. 2 is a vertical sectional view through the latch in the position shown in Fig. 1;

40 Fig. 3 is a section on the line 3—3 of Fig. 2; and

Fig. 4 is a section on the same lines as Fig. 2 but showing the upper sash raised and the latch device thrown out of its latching position.

Referring to these drawings, 10 designates a supporting casing comprising a base 11, an upwardly extending rear wall, and lateral walls 12. This casing or support is provided with laterally disposed wings 13 through which fastening screws 14 pass, as illustrated in Fig. 3. The outer edge faces of the wings or flanges 12 extend downward and outward and the base 11 does not extend out to the outer edge faces of the walls 12. The support is set slightly inward from the

upper corner of the meeting rail A of the upper sash, preferably about $\frac{1}{8}$ ".

Pivottally mounted between the lateral walls 12 is a tongue 15, the pivotal point 60 of this tongue being approximately in line with the upper face of the base 11. This tongue is rounded upon its inner end and is formed with an angularly projecting lug 16. The extremity of the tongue is provided 65 with an outwardly projecting lug 17 extending parallel to the lug 16 and the tongue is formed intermediate of its length with a recess 18. The tongue also carries upon its inner face a lug 19 which is disposed adjacent the rear end of the tongue and pivoted to this lug 19 is a locking member 20 having upon one face the finger hold 21. When this locking member 20 is disposed in a horizontal position and upon the tongue 15, this 70 finger hold 21 is accommodated by the recess 18. When the locking member 20 is disposed as illustrated in Fig. 2, however, and in locking position, this finger hold extends upward and forms means whereby the 75 locking member may be manually released from its locking position.

It is to be noted that when the tongue 15 is in its horizontal position, the lug 16 extends downward and that when the tongue 15 85 is in an approximately vertical position, as illustrated in Fig. 4, the lug 16 extends forward. The length of this lug 16 is such that when it is extended forward or outward, as in Fig. 4, the point of the lug is 90 just within the plane of the adjacent face of the window sash, that is, just within a vertical plane, including the upper corner of the meeting rail A. The locking member 20 and the tongue 15 have a width approximately equal to the width between the walls 12, so as to move snugly therein, but freely.

Attached to the meeting rail B is a striking plate 22, which has a length equal to the entire length of the base of the support 10 100 and which is held by screws 23 or other fastening devices to the upper face of the meeting rail B. This striking plate 22 projects slightly beyond the upper corner of the meeting rail B and preferably the upper face 105 of the plate is cut away, as at 24, for a distance equal to the width of the tongue 15, the upper face of this cut-away portion being beveled inward. Now it will be seen from Fig. 2 that when the meeting rails A 110 and B are abutted against each other, the tongue 15 will extend over the face of the

striking plate 22 with the lug 17 extending downward over the outer edge face of the striking plate and binding thereon.

The practical use of this invention will be obvious from the drawings. When the sashes are closed, the parts are in the position shown in Fig. 2. The tongue 15 extends over the striking plate while the locking member 20 abuts against the rear wall of the support 10. Under these circumstances if it is attempted to raise the lower sash or lower the upper sash, the locking member 20 will bind against the rear wall 10 or any other suitable abutment, and will wedge and absolutely prevent any relative movement of the two sashes. If, however, the locking member 20 be shifted to the dotted line position shown in Fig. 2, then the lower sash can be raised or the upper sash lowered and as this occurs the tongue 15 will be lifted and eventually the tongue 15 and the locking member 20 will be shifted to the position shown in Fig. 4, entirely free of the lower sash, and the lower sash can then be raised or lowered within certain limits without affecting the latch at all. Now upon lowering the lower sash from the position shown in Fig. 4 to that shown in Fig. 2, the projecting edge of the striking plate 22 will strike the projecting lug 16 and cause the tongue to rotate or fall over to the position shown in Fig. 2, and as this occurs the pivotal support for the locking member 20 will move upward and then forward and as it moves forward, the locking member 20 will shift to the position shown in Fig. 2, wedging into place and the sashes will be locked from relative movement. When the locking tongue 15 is disposed as shown in Fig. 2, the lug 17 will engage over the edge face of the striking plate and will bind thereon and will thus positively prevent the window from rattling. It is to be understood that the striking plate 22 is wider than the tongue 15 and that as it projects beyond the edge of B along its entire extent, it will prevent a fine knife blade from being inserted between the meeting rails A and B to effect the lifting of the member 15 or of the locking member 20. This makes the device thief-proof from the outside.

While I have illustrated a construction which I have found particularly effective in actual practice, which may be cheaply made and which is easily attached to any make of window sash, yet I do not wish to be limited to the actual details illustrated as it is obvious that minor changes may be made in the details without departing from the spirit of the invention as described in the appended claims.

Having thus fully described my invention, what I claim is:

1. A sash fastener comprising a supporting member having a tongue pivoted to it

and normally disposed in a horizontal plane and adapted to overlie the lower sash of a window, the tongue being movable in a vertical plane to an approximately vertical position, a locking member hingedly mounted on the face of the tongue, said locking member when the tongue is in a horizontal position extending rearward and the locking member being of such length that its end face bears against the supporting member and thereby locks the tongue in a horizontal position, said locking member when the tongue is in an approximately vertical position extending parallel with the tongue and urging the tongue toward the supporting member, said tongue being formed at its pivotal end with a lug projecting downward when the tongue is in a horizontal position and outward when the tongue is in an approximately vertical position, and a striking plate adapted to be attached to the upper face of the meeting rail of a lower sash and project beyond said meeting rail to thereby engage said lug when the tongue is in an approximately vertical position and shift the tongue from its vertical position to a horizontal position, thereby causing the locking member to fall to its horizontal locking position.

2. A sash fastener comprising a supporting member having a tongue pivoted to it and normally disposed in a horizontal plane and adapted to overlie the lower sash of a window, the tongue being movable in a vertical plane to an approximately vertical position, a locking member hingedly mounted on the inner face of the tongue intermediate of its ends, said locking member when the tongue is in a horizontal position extending rearward and bearing against the supporting member to lock the tongue in a horizontal position, said tongue being formed at its pivotal end with a lug projecting downward when the tongue is in a horizontal position, and a striking plate adapted to be attached to the upper face of the meeting rail of the lower sash and project beyond said meeting rail to thereby engage said lug to shift the tongue from its approximately vertical position to a horizontal position, said tongue being provided at its free end with a lug projecting downwardly when the tongue is in a horizontal position and engaging against the edge face of the striking plate.

3. The combination with the upper and lower sashes of a window including meeting rails, of a supporting member mounted upon the meeting rail of the upper sash and having a portion extending in a vertical plane and parallel to the meeting rail of the window sash, a tongue hingedly connected to the supporting member and normally lying in a horizontal position over the upper face of the meeting rail of the lower sash, said tongue having a lug projecting from its

pivotal end, said lug projecting toward the meeting rail of the lower sash when the tongue is in an approximately vertical position, a locking member hingedly connected 5 to the opposite face of the tongue and extending rearward when the tongue is in a horizontal position, said locking member having a length such that the end face of the locking member bears against the confronting vertical face of the supporting member when the tongue is in a horizontal position to thereby lock the tongue in a horizontal position, and means mounted on the meeting rail of the lower sash engaging 10 said lug when the tongue is in an approximately vertical position and when the meeting rails of the sashes are brought into contiguity to thereby rotate the tongue to its horizontal locking position.

20 4. The combination with upper and lower window sashes having meeting rails, of a tongue pivotally mounted upon the meeting rail of the upper sash for movement in a vertical plane, said tongue when in a horizontal position extending over the meeting rail of the lower sash and being provided at its pivotal end with a lug extending downward when the tongue is in a horizontal position, a lug extending upward from the 25 upper face of the tongue when the latter is in a horizontal position, a locking member pivoted to said lug for movement in a vertical plane and adapted to engage with an abutment when the locking member is disposed in a horizontal plane to thereby prevent the rotation of the tongue from a horizontal position to a vertical position, a striking plate mounted upon the upper face 30 of the meeting rail of the lower sash and having its inner edge extending beyond the inner edge of the meeting rail and being adapted to engage the lug on the tongue when the sashes are shifted to bring the 35 meeting rails in alinement, to thereby cause the rotation of the tongue from its vertical to its horizontal position, the locking member having upon its outer face an upwardly projecting finger hold, and the tongue being 40 formed with a recess to receive said finger hold when the tongue is shifted into an approximately vertical position.

45

to its horizontal position, the extremity of the tongue being provided with a lug adapted to engage over the outer edge face of the striking plate when the tongue is in a horizontal position to thereby hold the 50 sashes from rattling.

5. The combination with upper and lower window sashes having meeting rails, of a tongue pivotally mounted upon the meeting rail of the upper sash for movement in a vertical plane, said tongue when in a horizontal position extending over the meeting rail of the lower sash and being provided at its pivotal end with a lug extending downward when the tongue is in a horizontal position, a lug extending upward from the upper face of the tongue when the latter is in a horizontal position, a locking member pivoted to said lug for movement in a vertical plane and adapted to engage 55 with an abutment when the locking member is disposed in a horizontal plane to thereby prevent the rotation of the tongue from a horizontal position to a vertical position, a striking plate mounted upon the upper face 60 of the meeting rail of the lower sash and having its inner edge extending beyond the inner edge of the meeting rail and being adapted to engage the lug on the tongue when the sashes are shifted to bring the 65 meeting rails in alinement, to thereby cause the rotation of the tongue from its vertical to its horizontal position, the locking member having upon its outer face an upwardly projecting finger hold, and the tongue being 70 formed with a recess to receive said finger hold when the tongue is shifted into an approximately vertical position.

In testimony whereof I hereunto affix my signature in the presence of two witnesses. 75

WILLIAM S. FELL.
